United States Patent Office.

JOHN D. MUNSON, OF TYRE, NEW YORK.

Letters Patent No. 66,164, dated June 25, 1867.

SHEEP-RACK.

The Schedule referred to in these Letters Patent and making part of the same.

TO ALL WHOM IT MAY CONCERN:

Be it known that I, JOHN D. MUNSON, of Tyre, in the county of Seneca, and State of New York, have invented a new and useful improvement in Sheep-Racks; and I do hereby declare that the following is a full, clear, and exact description thereof, which will enable others skilled in the art to make and use the same, reference being had to the accompanying drawings, forming part of this specification, in which—

Figure 1 is a vertical longitudinal central section of my improved sheep-rack, taken through the line *z z*, fig. 2.

Figure 2 is a vertical cross-section of the same, taken through the line *y y*, fig. 1.

Similar letters of reference indicate like parts.

My invention has for its object to furnish a simple and convenient rack for feeding sheep with hay or grain, and which can be readily taken apart for storage; and it consists in the construction of the frame of the rack; in the combination of the pivoted slat frames or racks with the frame of the rack; in the combination of the division-board or frame with the frames of the rack; and in the combination of the hinged boards with the division-boards or frames and with the frames of the rack; the whole being constructed and arranged as herein-after more fully described.

A and B are the frames of the rack. The frame A is made a little shorter than the frame B, so as to fit into it, and the said frames are secured or pivoted to each other by pins or bolts passing through the middle parts of their end-pieces, as shown in fig. 2. This construction enables the rack to be readily taken apart, so that it can be stored away in a small space. C and D are the slot frames, which are attached to the bars or rollers *c'* and *d'*, the ends of which are pivoted to the upper parts of the end-pieces of the frames A and B, so that the said slat frames may be turned over to clean out the rack or to shut the sheep out from the grain-troughs. When the slat frames C and D are in proper position to receive the hay their lower ends rest against the lower side-bars or boards, *a'* *b'*, of the frames A and B, and their middle parts rest upon the bars *a''* and *b''* of said frames. E and F are the division-boards or frames, the ends of the longitudinal bars or boards of which enter slots in the end timbers of the frames A and B, and the cross-bars of which project upward to prevent the sheep from interfering with each other while feeding. The end cross-bars of the frames E and F extend upward so as to enter notches in the outer edges of the end-pieces of the frames A and B, so as to support the upper parts of said frames. To the lower edges of the longitudinal boards *a'* and *b'* of the frames A and B, are hinged the lower edges of the boards G and H, which, when in one position, form the outer sides of the chaff-troughs, and when in another position, form the inner sides of the grain-troughs. To the lower edges of the boards G and H are attached the narrow boards I and J, which form the bottoms of the grain-troughs. In using the rack for feeding hay the parts are arranged in the position shown in the drawings. The hay is put into the rack and the sheep draw it out at the lower part, the chaff-troughs formed by the boards *a'* and G, and by the boards *b'* and H, receiving the leaves and seed of the hay. To feed grain the boards G and H are moved towards the boards *a'* and *b'* respectively. This brings the projecting edges of the boards I and J in contact with the horizontal boards of the frames E and F, where they are secured in place by the buttons K and L, pivoted to the lower edges of the said boards E and F. The slat frames are then turned down so as to hang outside of the frames E and F, to keep the sheep away from the grain-troughs while the grain is being put into the said troughs. The grain is then poured over the rollers *c'* and *d'*, so as to fall outside of the bars *a''* and *b''* into the grain-troughs. The slat frames are then swung back to their places, allowing the sheep to have access to the grain.

What I claim as new, and desire to secure by Letters Patent, is—

1. The combination of the pivoted slat frames or racks, C and D, with the frames A and B, substantially as herein shown and described, and for the purposes set forth.
2. The combination of the division-boards or frames, E and F, with the frames A and B of the rack, substantially as herein shown and described, and for the purpose set forth.
3. The combination of the hinged boards G I and H J with the frames A and B, and with the division-boards or frames E and F, substantially as herein shown and described, and for the purpose set forth.
